CHARGED-PARTICLE ENERGY METER

John H. Coleman, Princeton, N. J., assignor to
 Radio Corporation of America, a corporation
 of Delaware

Application April 1, 1949, Serial No. 84,785

17 Claims. (Cl. 250—83.6)

1

This invention relates generally to charged-particle energy meters and more particularly to such meters in which the energy of the radiated particle is determined as a function of the ratio of the secondary electron emission to the primary radiation, following the particles bombarding a target.

It is known that when a surface is bombarded by radiated nuclear particles, secondary electrons are emitted into space from the surface. Even materials that are classed generally as insulators are subject to some secondary electron emission upon bombardment by charged particles.

The number of secondary electrons emitted from a surface per individual bombarding particle, which defines the secondary emission ratio ds , varies for an individual material with the energy of the incident particles. Also, the secondary emission ratio varies among different materials for the same incident energy. And, the variations in the secondary emission ratio for low energy particles is inherently different from the variations for high energy particles for the same material.

The present invention, provides a novel method of and apparatus for determining the secondary electron emission ratio when a target of known material is bombarded by a beam of charged particle radiation of known energy, from which may be determined the relation of the secondary emission ratio to the energy of the particles for various target materials and the relation of the secondary emission ratio to the atomic weight of the material of which the target is made, for various particle energy values. These data in the form of curves are then available for use as a step in the method of determining the unknown energy values of a charged particle radiation, that is, of determining the energy of the radiation particles in electron volts.

The principal object of the invention is to provide a novel method of and apparatus for determining the energy of the particles in a charged particle radiation.

Another object of the invention is to provide a novel method of and apparatus for determining the secondary emission ratio of a target bombarded by nuclear charged particles.

Another object of the invention is to provide a novel method of and apparatus for determining the secondary emission ratio of a target bombarded by primary charged particles and from the determined ratios, determine the energy of the unknown primary particle radiation.

Another object of the invention is to provide a

2

novel method of and apparatus for determining the secondary emission ratio of a target bombarded by nuclear charged particles by utilizing two targets of dissimilar materials.

5 Other objects will be apparent from the description of the invention as hereinafter set forth in detail and from the drawings made a part hereof in which:

Figure 1 is a schematic sketch of a side view of 10 the basic embodiment of the invention illustrating the arrangement of the target, the collector for the secondary emitted emissions, and the associated circuits;

Figure 2 illustrates by curves typical relations 15 of the secondary emission ratios to the various bombarding energies for several target materials;

Figure 3 is a schematic sketch of a face view of 20 the same general arrangement as shown in Figure 1, except that the target is composed of two semicircular discs of different materials and with separate recording circuits for each target;

Figure 4 is a graph showing the relation of the 25 secondary emission ratios to the energies of the primary particles for two materials being bombarded at relatively low energy values;

Figure 5 is a schematic sketch of a face view of 30 the same general arrangement as shown in Figure 1, except that the target is composed of relatively narrow strips of two different materials, forming in general a circular disc target, the alternate strips being connected together and to exterior circuits;

Figure 6 is a schematic sketch of a side view of 35 a modification of device in Figure 1 in which the collector is spherical and transparent to high energy particles;

Figure 7 is a schematic sketch of a further 40 modification of the device shown in Figure 1, in which the collector is shown as a truncated hollow cone;

Figure 8 is a schematic sketch of a multi- 45 kinetic beam of charged particles being separated by a magnetic field and showing the position of the collector relative to the separated beam; and

Figure 9 illustrates the relation by a curve of 50 secondary emission ratios to the atomic weight of the target material for a constant energy of the bombarding particles.

Similar reference characters are applied to similar elements throughout the drawings.

Referring to Figure 1, the arrows, numeral 10, represent two of the paths of charged particle radiation, for example, electrons bombarding target 11. In describing the basic embodiment

of the invention, the radiation will be assumed to be mono-kinetic. This primary radiation causes secondary electrons to be emitted within the evacuated envelope 9 from dynode target 11, the paths of four of which are shown as arrows 12. The electrons leave target 11 at various velocities, from nearly zero to approximately the velocity of the primary particles, and are collected by the flat ring like collector 13, which is biased positive by being connected to electric source 14, the negative side of which source is connected to ground 15 through ammeters 16 and 17 and to target 11 through ammeters 16 and 18. Ammeter 16 is connected between collector 13 and ammeter 17 to measure the secondary emission current ids . The currents flowing to and from target 11 are in proportion, respectively, to the captured primary electrons bombarding the target 11, forming primary current ip , and the secondary electrons emitted from the target 11 and collected by collector 13, forming current ids . The net current flowing to target 11 is ip minus ids . The current flowing through ammeter 17 to point 19 is equal to the sum of the currents flowing through ammeters 16 and 18 away from point 19, or in minus ids plus ids , or ip .

There is thus provided circuits and instruments to measure the primary current ip and secondary current ids . By definition, the secondary emission ratio is equal to ids divided by ip .

These secondary emission ratio data constitute the "characteristics" of the target under the observed conditions. The data may be assembled in the form of tables or curves or families of curves and thus these data become available to determine the unknown energy of the particles of the radiation when the secondary emission ratio of that radiation is observed from targets of known materials.

The family of curves in Figure 2 are determined by exposing targets to known energy radiations, the targets being made of various elements, such as tungsten or graphite, or compounds of elements, such as steel or beryllium oxide, and plotting the relations of the secondary emission ratio to the energies of the particles.

The energy of an unknown radiation may then be determined by entering the curve, as shown in Figure 2, by drawing a horizontal line on the figure corresponding to the determine value of ds and picking off the corresponding value of energy of the primary electrons on the curve of the material of target 11.

Referring to Figure 3, there is illustrated therein a modification of the device shown in Figure 1, in which the target is composed of two semi-circular dynode discs 11a and 11b, made of different materials, for example, beryllium and carbon, respectively. These targets are separated in space and are connected, through ammeters 18a and 18b, respectively, to point 19. Collector 13 collects the secondary electrons emitted from both targets 11a and 11b and is connected to point 19 through biasing electric source 14 and ammeter 16. Point 19 is connected to ground 15 through ammeter 17.

From the analysis hereinbefore of the primary particle currents and the secondary emission currents, ammeter 16 will register the sum of the secondary currents, isa and isb ; ammeter 18a will register the currents ipa minus isa ; ammeter 18b will register the currents ipb minus isb and ammeter 17 will register the primary currents ipa plus ipb .

In operation: Having determined by observation the values of ipa minus isa and ipb minus isb , collector 13 is biased sufficiently negative to suppress secondary currents isa and isb , which is determined by increasing the bias on collector 13 until ammeter 16 reads zero. The values of ipa and ipb are then observed by reading ammeters 18a and 18b, respectively. The differences, then, between the secondary emission ratios of the two targets, dsa minus dsb , may be determined by

$$dsa - dsb = \frac{isa}{ipa} - \frac{isb}{ipb} \quad (1)$$

The observed data and the calculated value of dsa minus dsb are used to determine the energy of the bombarding particles by applying the difference to curves plotting the relation of ds to particle energy for the two materials of the target, 11a and 11b, such as shown in Figure 2. There is enough divergence in the curves for the various materials to determine the particle energy. For example, if target section 11a is made of graphite and 11b is made of beryllium and the calculated value of dsa minus dsb of a length on the scale of ds as shown by dotted lines in Figure 2, this dotted line is moved across the space between the curves for graphite and beryllium until it terminates in the two curves. The downward projected points on the curves to the abscissa Mev will then indicate the value of the energy of the bombarding particles.

The relations between the secondary emission ratio and the energy of the bombarding particles varies greatly for the different materials of the target for the lower energy values. The curves for these values of bombarding energy are of the same general shape, having a rise to a peak and a decline at a less rapid rate for further increases in bombarding energies.

Advantage may be taken of the characteristic curves of different materials, such as shown in Figure 4, in which curve 20 is a plot of ds versus ev for beryllium oxide on a beryllium dynode and curve 21 is a similar plot for graphite. Not only do these curves vary greatly between themselves, due principally to variations in particle capture, but the curves vary greatly in their slope, thus increasing the accuracy of fitting the values of dsa minus dsb to the curves to pick off from the curves the value of ev .

In the determining of the value of ev in the example shown in Figure 4, the value of dsa minus dsb may fit between the curves in more than one value of ev . The value of ev is generally known within general limits so that the proper position may be selected, with aid in selection by knowing whether the values of dsa minus dsb is decreasing or increasing, and applying the value according to the relative slopes of the curves.

When it is desired to determine the energy values of an inhomogeneous energy radiation, the rays are passed through a magnetic field, shown generally at 22, Figure 8. The rays are directed through the field at right angles to the magnetic lines of force and their paths are bent inversely as their energy values. By making the magnetic field of sufficient value, the beam is spread out to such an extent, that the rays of the beam are mono-kinetic at various positions around an arc relative to the point where the beam enters the magnetic field. The target 11 may be moved progressively into the paths of rays 10a, 10b,

10c etc., and the energy values of the component parts of the beam may be determined.

Other embodiments of the invention are obvious, for example, as disclosed in Figures 5, 6 and 7.

With reference to Figure 5, the two sections of the target, 11a and 11b, made of different materials as hereinbefore disclosed, are divided up into strips, narrow in proportion to the diameter of the beam. These strips of two different materials are mounted alternately across the beam and are connected together as shown at point 19 through ammeters 18a and 18b, respectively. Collector 13 is biased by electric source 14 and is connected to point 19 through ammeter 16. Point 15 is grounded at 15 through ammeter 17.

The secondary emission electrons are collected generally uniformly over the beam area, even though target 11a is of different material from target 11b. The primary current, indicated by ammeter 17, is, therefore, equally divided between the two target circuits. The current flowing through ammeter 18a is $ip/2$ minus isa ; the current flowing through ammeter 18b is $ip/2$ minus isb ; and the current flowing through ammeter 16 is isa plus isb .

By definition ds equals the secondary current divided by the primary current. Therefore,

$$ds_a - ds_b = \frac{isa}{ipa} - \frac{isb}{ipb} \quad (2)$$

and as ipa equals ipb and equals ip divided by 2,

$$ds_a - ds_b = \frac{2isa}{ip} - \frac{2isb}{ip} \quad (3)$$

Determining ip by observation of ammeter 17, the values of isa and isb are determined from observations of ammeters 18a and 18b, respectively. With these values, ds_a and ds_b are determined from Equation 3 and the value of the energy of the radiation particles is determined as heretofore disclosed.

In Figure 6 is disclosed an embodiment of the invention for use with high energy radiation. The collector 13 is made thin enough, for example, .001" aluminum or beryllium, so that it does not materially slow down the radiation rays 10 bombarding target 11, but thick enough to collect secondary electrons 12. The remainder 23 of the envelope 9 is made of some insulating material and the envelope is evacuated. Connections to and from electric source 14, ammeters 16, 17 and 18, and ground 15 are the same as disclosed in connection with Figure 1.

In Figure 7 is shown another embodiment of the invention wherein the collector 13 is in the form of a truncated cone made of sheet material. The evacuated envelope 9 consists of a thin window 24 and a section 23, as described in connection with Figure 6. By making the envelope out of a material that would absorb radiation without secondary emission or by grounding section 23, the section 23 will shield collector 13 from bombardment by stray rays in the radiation beam.

It should be understood that either an externally or internally disposed electron multiplier arrangement may be combined with any of the embodiments of the invention described heretofore to provide any desired degree of current amplification of the secondary electrons released from the radioactive target 11.

Data is also obtainable, as hereinbefore disclosed, to plot the relation of the secondary emission ratio ds versus atomic weights of elements

of the target for a constant energy of particle bombardment.

Figure 9 is a typical curve of ds versus atomic weights of the target for a constant energy value of 300,000 ev. A family of curves for other constant values of the energies of the bombarding particles may be plotted. Having determined by a device such as shown in Figures 1, 6 or 7, the value of ds for an unknown particle energy value the plot is entered on the abscissa corresponding to the atomic weight of the material of the target, line 25, and the plot is entered on the ordinate corresponding to the observed value of ds , line 26, and the value of the primary particle energy determined.

There is thus disclosed a unique method of and apparatus for determining the values of the secondary emission ratio for known radioactive radiation from which data may be obtained to determine the values of unknown radioactive radiations.

What is claimed is:

1. The method of determining the unknown energy of nuclear charged particle radiation comprising: determining the secondary emission ratio for known energy particle radiation bombarding targets of known material, determining the secondary emission-energy characteristics of said known targets, bombarding a target of known material by the said unknown energy radiation and determining the secondary emission ratio thereof, and applying said last mentioned ratio to said characteristics, whereby the corresponding energy of said particles of unknown energy is determined.

2. The method of determining the unknown energy of nuclear charged particle radiation comprising: determining the secondary emission ratio for known energy particle radiation bombarding targets of known elements, plotting said determinations in curves having as one variable the secondary emission ratio and as the other variable the particle energy, bombarding a target of known material by the said unknown energy radiation and determining the secondary emission ratio thereof, and applying said last mentioned ratio to said curves, whereby the corresponding energy of the said particle of unknown energy is determined.

3. The method of determining the unknown energy of nuclear charged particle radiation comprising: determining the secondary emission ratio for known energy particle radiation bombarding targets of known compounds of elements, plotting said determinations in curves having as one variable the secondary emission ratio and as the other variable the particle energy, bombarding a target of known material by the said unknown energy radiation and determining the secondary emission ratio thereof, and applying said last mentioned ratio to said curves, whereby the corresponding energy of said particles of unknown energy is determined.

4. The method of determining the unknown energy of nuclear charged particle radiation comprising: determining the secondary emission ratio for known energy particle radiation bombarding targets of known compounds of elements, plotting said determinations in curves having as one variable the secondary emission ratio and as the other variable the particle energy, bombarding a plurality of said targets of known secondary emission characteristics by the said unknown energy radiation and determining the secondary emission ratios thereof, and applying the differences be-

tween said determined ratios to said curves, whereby the corresponding energy of the said particles of unknown energy is determined.

5. The method of determining the unknown energy of nuclear charged particle radiation comprising: determining the secondary emission ratio for known energy particle radiation bombarding targets of known elements, plotting said determinations in curves having as one variable the secondary emission ratio and as the other variable the particle energy, bombarding a plurality of said targets of known secondary emission characteristics by the said unknown energy radiation and determining the secondary emission ratios thereof, and applying the differences between said determined ratios to said curves, whereby the corresponding energy of the said particles of unknown energy is determined.

6. The method of determining the ratio of secondary electron emission of a target exposed to primary charged particle radiation comprising: collecting the said secondary electrons on an electrode and conducting them to a point, conducting the free electrons on said target to said point, and grounding said point, the said ratio being the value of said collected current divided by the value of said ground current.

7. The method of determining the ratio of secondary electron emission of a target exposed to primary charged particle radiation comprising: collecting the said secondary electrons on an electrode and conducting them to a point, biasing said electrode with respect to said target, conducting the free electrons on said target to said point, and grounding said point, the said ratio being the value of said collected current divided by the value of said ground current.

8. In a radioactive charged particle radiation energy meter including a target of two sections of dissimilar materials and a collector adjacent thereto, the method of determining the unknown charged particle energy of said radiation comprising: determining the secondary emission ratios for known nuclear particle energy radiation for the two target materials, plotting said determinations in curves having as one variable the secondary emission ratios and as the other variable the particle energy, bombarding the said target by the unknown energy radiation and determining the difference between the secondary emission ratios of the two sections of the target, and applying the said determined difference to said curves, whereby the corresponding energy of the particles of unknown energy is determined.

9. In an electronic device including a source of nuclear charged particle radiation, a secondary emission responsive target bombarded by said radiation, the said target consisting of a pair of separated semicircular sections *a* and *b* of different known secondary emission responsive characteristics and a collector for said emission, the method of determining the energy of said radiation comprising: bombarding said sections by said radiation, collecting said secondary emission currents from said targets separately and conducting them separately to a point, conducting the free electron currents from said sections separately to said point, grounding said point, thereby conducting currents from said point to ground (*ipa* plus *ipb*), biasing the said conductor with increasing negative potential until the said collecting currents are zero, whereby the currents from said points to said sections are reduced respectively to the primary currents flowing to said sections (*ipa* and *ipb*), the difference between the

secondary emission ratio being defined by the equation

$$ds_a - ds_b \text{ equals } \frac{isa}{ipa} - \frac{isb}{ipb}$$

and applying said difference to said characteristics whereby the energy of the particles of said radiation is determined.

10. In an electronic device including a source of nuclear charged particle radiation, a secondary emission responsive target bombarded by said radiation, the said target consisting of a pair of separated semicircular sections *a* and *b* of different secondary emission responsive materials and a collector for said emission, the method of determining the difference between the secondary emission ratios of said sections (*ds_a* and *ds_b*) bombarded by a radiation of unknown energy, comprising: collecting said secondary emission currents from said targets (*isa* and *isb*) and conducting them separately to a point, conducting the free electron currents from said target sections separately to said point, grounding said point thereby conducting currents from said point to ground (*ipa* plus *ipb*), biasing the said collector with increasing negative potential until the said collecting currents are zero, whereby the currents from said points to said sections are reduced respectively to the primary currents flowing to said sections (*ipa* and *ipb*), the difference between the secondary emission ratios being defined by the equation:

$$ds_a - ds_b = \frac{isa}{ipa} - \frac{isb}{ipb}$$

11. In an electronic device including a source of nuclear charged particle radiation, a secondary emission responsive target bombarded by said radiation, the said target consisting of a plurality of alternately positioned strips of different known secondary emission responsive characteristics and a collector for said emission, the method of determining the energy of the particles of said radiation comprising: collecting separately the said secondary emission currents *isa* and *isb* and conducting them to a point, conducting the free electron currents from said target sections separately to said point, grounding said point thereby conducting currents from said point to ground (*ip*), the difference between said secondary emission ratio being defined by the equation:

$$ds_a - ds_b \text{ equals } \frac{2(isa)}{ip} - \frac{2(isb)}{ip}$$

and applying said difference to said characteristics whereby the energy of said radiation is determined.

12. In an electronic device including a source of nuclear charged particle radiation, a secondary emission responsive target bombarded by said radiation, the said target consisting of a plurality of alternately positioned strips of different known secondary emission responsive characteristics, and a collector for said emission, the method of determining the difference between the secondary emission ratios of said sections (*ds_a* and *ds_b*) bombarded by a radiation of unknown energy, comprising: collecting separately the said secondary emission currents *isa* and *isb* and conducting them to a point, conducting the free electron currents from said target sections separately to said point, grounding said point thereby conducting currents from said point to ground (*ip*), the dif-

ference between the secondary emission ratios being defined by the equation:

$$dsa - dsb = \frac{2(isa)}{ip} - \frac{2(isb)}{ip}$$

13. In an electronic device including a source of charged particle radiation, a secondary electron emission responsive target bombarded by said radiation, and a collector for said secondary electron emission, the method of determining the ratio of said secondary emission currents to said primary radiation currents comprising: conducting currents from said collector and currents from said target to a grounded common point, determining the currents flowing from said collector to said point and from said point to said ground, the said ratio being the value of said collector currents divided by the value of said ground currents.

14. In combination: a source of radioactive charged particle radiation, a secondary emission responsive means exposed to said radiation, means for collecting said emission, the said emission means and said collecting means being connected together at a point and the said point being grounded, and means for measuring the currents flowing to and from said point.

15. The combination defined by claim 14 characterized by the collection means being a hollow truncated cone positioned adjacent said responsive means, the axis of said cone being at right angles to the plane of said responsive means and at the center thereof.

16. In combination: a source of radioactive charged particle radiation, a secondary emission responsive means exposed to said radiation, the

said responsive means consisting of two semicircular discs of different secondary emission responsitivity, a collector positioned adjacent said responsive means, means for connecting each of said discs to a point, means including a biasing electric source connecting said collector to said point, means including a current measuring device connecting said point to ground, and means for measuring respectively the currents flowing between said point and said discs.

17. In combination: a source of radioactive charged particle radiation, a secondary emission responsive means exposed to said radiation, the said responsive means consisting of two sets of strips of different secondary emission ratio responsitivity positioned alternately across the said radiation, the alternate strips being connected together, means for connecting respectively each said set of strips to a point, means including a biasing electric source connecting said collector to said point, means including a current measuring device connecting said point to ground, and means for measuring respectively the currents flowing between said point and said discs.
